(57) **CLAIM**

We claim the ornamental design for a protective case for an electronic device, as shown and described.

DESCRIPTION

FIG. 1 is a perspective view of a protective case for an electronic device showing our new design;

FIG. 2 is a front plan view thereof;

FIG. 3 is a rear plan view thereof;

FIG. 4 is a left side elevation view thereof;

FIG. 5 is a right side elevation view thereof;

FIG. 6 is a top elevation view thereof; and,

FIG. 7 is a bottom elevation view thereof.

The portions shown in broken lines are included for illustrative purposes and form no part of the claimed design.
